DESIGN FOR A PITCHER OR SIMILAR ARTICLE

Dodson Haslup, Grafton, W. Va.

Application July 1, 1939, Serial No. 85,799

Term of patent 14 years

To all whom it may concern:

Be it known that I, Dodson Haslup, a citizen of the United States and residing in the city of Grafton, in the county of Taylor and State of West Virginia, have invented a new, original, and ornamental Design for a Pitcher or Similar Article, of which the following is the specification, reference being had to the accompanying drawing, forming a part thereof.

In the drawing:

Figure 1 is a side elevational view of a pitcher or similar article showing my design.

Figure 2 is an end elevational view of the pitcher looking at the side bearing the handle.

Figure 3 is a top plan view thereof on an enlarged scale.

I claim:

The ornamental design for a pitcher or similar article, substantially as shown.

DODSON HASLUP.
